W. G. BUCK

VALVE ROTATOR

Filed May 25, 1920

UNITED STATES PATENT OFFICE.

WILMER G. BUCK, OF FREMONT, NEBRASKA, ASSIGNOR TO CONTINENTAL ENGINEERING CORPORATION, OF OMAHA, NEBRASKA, A CORPORATION OF NEBRASKA.

VALVE ROTATOR.

Application filed May 25, 1920. Serial No. 384,177.

To all whom it may concern:

Be it known that I, WILMER G. BUCK, a citizen of the United States, residing at Fremont, in the county of Dodge and State of Nebraska, have invented certain new and useful Improvements in Valve Rotators, of which the following is a specification, reference being had therein to the accompanying drawing.

10 This invention deals with an improved device for rotating valves of the poppet type used more particularly in connection with an internal combustion engine.

The use of the device has proven to be an 15 effective means for maintaining the contacting surfaces of the valve and its seat in their highest state of efficiency by preventing the accumulation of foreign deposit therebetween.

20 Broadly speaking, the results attained in the present case have heretofore been attempted but as a general rule these prior devices are either of an extremely complicated nature or else require a change, more or less, in the standard construction of the valve to enable their attachment thereto; also, in some instances, the operation of the device is accompanied by a metallic click between certain of the loose parts thereof. Any one 25 of these disadvantages is sufficient to cause their rejection for adaption to the high standard of internal combustion engine constructions used in automobiles of today.

It is therefore the main aim of the present 30 invention to provide a rotator of extremely simple construction, consisting of a minimum number of parts, cheap to manufacture, and easy to assemble, which when attached in place works in a highly efficient 35 and durable manner.

Another object of the invention resides in the novel manner of causing a step by step rotation of the valve during the normal operations thereof, which results in a slight 40 wiping action of the valve head against its seat during the seating stroke of said valve, thereby removing any sediment or deposit 45 that may happen to find lodgment on either the valve face or its seat.

50 Another object of the invention resides in the novel manner of eliminating the objectionable click between the metallic parts of the device during the actuation thereof.

Another object attained in the present invention is the ability to adjust the degree of 55 rotation of the valve during its operations.

Other objects and aims of the invention more or less broader than those stated above, together with the advantages inherent, will be in part obvious and in part specifically 60 referred to in the course of the following description of the elements, combinations, arrangement of parts, and application of principles constituting the invention, and the scope of the invention contemplated will 65 appear from the claims.

In the accompany drawings which are to be considered in connection with the following detailed description, there is shown the preferred embodiment of the invention, used 70 in connection with an internal combustion engine, but it will of course be understood that the device is applicable to any type of power engine using reciprocating valves. The drawings should, therefore, be considered 75 simply as illustrative and not in a limiting sense.

In these drawings:—

Figure 1 is a fragmentary transverse sectional view of an engine showing the valve 80 rotator in elevation as applied to the valve stem.

Figure 2 is an enlarged sectional view through the rotator as applied to the valve 85 stem.

Figure 3 is a side elevation of the loosely mounted member and the ring which coacts therewith.

Figure 4 is a transverse section taken on line 4—4 of Fig. 2 looking in the direction 90 as indicated.

Figure 5 is a top plan view of the cap.

Figure 6 is a plan and also a side elevation of the washer employed in this case.

Figure 7 is a plan view showing both the 95 affixed member and also the movable member provided with the co-active inclined surfaces.

Referring now more specifically to the drawings, 10 indicates generally the cylinder of the engine in which the usual piston 100 11 operates and secured, or cast integral with the cylinder, is the valve casing 12

having the usual seat 13 therein. Cooperating with the valve seat 13 is the headed end 14 of the reciprocating valve 15, the opposite end of the valve 15 being actuated by the 5 tappet 16. All of these parts being of the standard construction no claim thereto is made in the present application.

Keyed to the valve stem 15 by a cross key 17 is what I term an affixed member 18, 10 socketed or recessed as at 19 for the reception of certain operative elements of the device. This affixed member is provided with a peripheral flange 20, which is grooved as at 21 to form one face of a ball raceway, and 15 is also circumferentially reduced as at 22 for a purpose hereinafter described.

Loosely mounted on the valve stem is a member 23, one end of which is flanged as shown at 24, while the opposite end is provided with diametrically opposite lugs 25—25. When in assembled relation the flanged end of the loosely mounted member is positioned within the socketed or recessed portion of the affixed member and is held there- 25 in by a cap 26 which has a machine fit with the side walls of the affixed member 18. The end of the cap is slightly beaded or bent inwardly as designated at 27 to snap within the circumferentially reduced portion 22 30 when the cap is in applied position. The opposite end of the cap has cut out portions 28—28 to permit the passage of the cap over the lugs 25—25 during the assemblage of the parts.

25 In order that the loosely mounted member be positively oscillated during the operations of the valve, a bushing illustrated at 29, is keyed in any suitable manner to the valve casing to prevent relative rotation thereof. 40 The side walls of the bushing are slotted as shown at 30—30 for the reception of the lugs 25—25 on the loose member. As will be noted, the side walls of the lugs 25—25 are flattened and at a pitch in keeping with the 45 angularity of the slots 30—30. This increases the line of contact between these parts, which materially reduces the degree of wear therebetween.

Also arranged within the socketed or recessed portion 19 of the affixed member 18 and beneath the flanged end 24 of the loosely mounted member 23, is a ring 31, which ring is frictionally held in position within the socket 19 and against the base thereof by 50 a spring band 32 or the like. This band 32 is angled at one end as shown at 33, which is adapted to be inserted within a cross cut 34 in the periphery of the ring 31. The purpose of this band 32 is merely to prevent independent movement of the ring within the recessed portion 19 during the reciproca- 55 tory action of the valve.

60 The adjacent faces of the flanged end 24 and the ring 31 are provided with a series of oppositely inclined surfaces 35 and 36, re-

spectively, the depths of the inclined surfaces being greater than the intervening space 37 between the top of the flanged end and the inner face of the overlying portion of the cap 26. If desired, a washer, as 70 shown at 38, may be inserted within the cap for the purpose of bridging the spaces or cut out portions 28—28 therein, thereby increasing the area of surface contact between the parts during operation. This washer is 75 made in two parts as shown in the drawings for the purpose of permitting its insertion into the cap 26 after the latter has passed over the lugs 25—25 on the member 23. When in applied position the peripheral 80 edges of the washer 38 are adapted to rest on the upper edge of the walls of the socket 19 and are securely held thereon by the binding action of the cap 26. This sectional washer 38 is provided with thickened portions 85 39—39 which are adapted to snugly fit within the cutouts 28—28 in the cap, thereby preventing relative movements between the washer and cap.

Loosely arranged upon the affixed member 18 above the peripheral flange 20, is a ring 40, the inner face of which is grooved as at 41 to constitute the opposite wall of the ball raceway. Suitable bearings illustrated at 42 are positioned in the grooves 21 and 41 to relieve the device from any frictional contact arising from the expansion spring 43 which rests at one end against the outer face of the ring 40 and at its opposite end against the valve casing.

Assuming that the parts are assembled and connected with the valve stem as shown in Figures 1 and 2 the complete operation of the device is as follows:

On the opening movement of the valve the lugged portions 25—25 on the loosely mounted member 23 engage in the slots 30—30 of the bushing 28 and cause a rotation of the sleeve 23, which results in the riding of the inclined surfaces 35 and 36 one upon the other to such an extent to force the flanged end 24 against the inner face of the washer or cap and the lower face of the ring 31 against the inner wall of the recess 19. In this position, all of the parts are 105 frictionally bound together so that the continued upward movement of the stem will result in a slight forward impulse or 110 rotative action being given thereto. During the high speed of the engine this slight rotating 115 action is sufficient to cause the parts to continue rotation on the down or closing stroke of the valve, so that a wiping action takes place between the valve face and its seat just as the valve is closing. On the down stroke of the valve, the lugs 25—25, being in engagement with the slots 30—30, cause a 120 rotative action to take place in the opposite direction, which initially uncouples the parts and on riding down the inclined sur- 125 130

faces and by engaging the shoulders thereof, the rotative action imparted to the loosely mounted member advances the ring 31 slightly to correctly position the same for 5 the next up or opening stroke of the valve.

While I have described and shown the device attached to an L-head type of engine, it is to be understood that the same principal might just as well be incorporated and with 10 the same efficiency on an engine employing the overhead system of valves; in fact, it may be used on any type of reciprocating valve and function in the same manner as herein described.

15 Having thus fully described my invention what I claim and desire to secure by Letters Patent is:—

1. The combination with a valve adapted to have opening and closing movements, a 20 casing secured to the valve stem of means for otherwise moving the valve comprising axially aligned cooperating parts arranged within the casing and adapted to frictionally engage to effect rotation of the valve and 25 subsequent release thereof during the cycle of movements of the valve.

2. The combination with a valve adapted to have opening and closing movements, a casing secured to the valve stem of means 30 for otherwise moving the valve intermittently comprising axially aligned cooperating parts arranged within the casing and adapted to frictionally engage to effect rotation of the valve and subsequent release thereof during 35 the cycle of movements of the valve.

3. A combination with a valve adapted to have opening and closing movements, of means for otherwise moving the valve about its longitudinal axis comprising a casing affixed to the valve, and axially aligned co-active parts therein adapted for frictional engagement with the casing during one of the movements of the valve to effect rotation of the valve and subsequent release thereof 40 during the cycle of movements of the valve.

4. The combination of a valve adapted to have opening and closing movements, of means for otherwise moving the valve intermittently about its longitudinal axis, comprising a casing affixed to the valve, and co-active parts therein adapted for frictional engagement with the opposite end walls of the casing during one of the movements of the valve to effect rotation of the valve and subsequent release thereof during the cycle 55 of movements of the valve.

5. The combination with a valve adapted to have opening and closing movements, of means for otherwise moving the valve, comprising a member affixed to the valve and having a relatively movable member co-axially aligned with the affixed member and adapted upon movement in one direction to frictionally bind the members and the valve 60 together to effect rotation of the valve and

subsequent release thereof during the cycle of movements of the valve.

6. The combination with a valve adapted to have opening and closing movements, of means for otherwise moving the valve comprising a casing affixed to the valve and a longitudinally shiftable part within said casing and adapted to frictionally engage with the casing to effect rotation of the valve when moved in one direction and subsequent release thereof when moved in the opposite direction. 75

7. The combination with a valve adapted to have opening and closing movements, of means for otherwise moving the valve comprising a member affixed to the valve stem, a second member loosely mounted on the valve stem, means for longitudinally shifting the loosely mounted member with respect to the affixed member during the opening and closing movements of the valve to frictionally lock and subsequently release the members to the valve to effect a rotation of the valve during the cycle of movements thereof. 80

8. The combination with a valve adapted to have opening and closing movements, of means for otherwise moving the valve intermittently, comprising axially aligned cooperating parts adapted for relative rotary and longitudinal shifting movements and by such movements to frictionally engage during one stroke of the valve and subsequent release thereof during the opposite movement of the valve. 85

9. The combination with a valve adapted to have opening and closing movements, a casing secured to the valve stem of means for rotating the valve during one of said movements comprising axially aligned cooperating parts arranged within the casing and adapted to frictionally engage and subsequently release the casing and thereby and the valve during the cycle of movements thereof. 100

10. In combination with a valve adapted to have opening and closing movements, a casing secured to the valve stem of means for otherwise moving the valve comprising axially aligned cooperating parts arranged within the casing and having oppositely disposed cammed surfaces adapted to effect a binding action between the parts and the casing during one of the movements of said valve and to subsequently release the parts during the opposite movement of the valve. 115

11. The combination with a valve adapted to have opening and closing movements, of means for otherwise moving the valve comprising a casing and cooperating parts within the casing having oppositely disposed cammed surfaces adapted to ride one upon the other during one of the movements of the valve to effect a frictional engagement between the valve and said parts and the casing and a subsequent release of the valve by the 125 130

reverse riding of said cam surfaces during the opposite movement of the valve.

12. The combination with a valve adapted to have opening and closing movements, of means for otherwise moving the valve, comprising a casing and cooperating parts within the casing having oppositely disposed cammed surfaces adapted to effect a frictional engagement between the valve and said parts and said casing when the valve is moved in one direction and to subsequently release the frictional engagement between the parts and the casing when the valve is moved in the opposite direction.
13. In a rotating device for a reciprocating valve comprising a member affixed to the valve stem, a second member loosely mounted on the valve stem, means for oscillating said second member during the operations of the valve, a casing secured to the affixed member for holding said members in operative relation to one another, and coacting means between the members for frictionally locking them with the valve when the second member is oscillated in one direction.
14. In a rotating device for a reciprocating valve comprising a member affixed to the valve stem, a second member loosely mounted on the valve stem, means for oscillating said second member during the operations of the valve, means carried by the affixed member for holding said members in operative relation to one another, and coacting means between the members for frictionally binding them to the valve when the second member is oscillated in one direction.
15. In a rotating device for a reciprocating valve comprising a member affixed to the valve stem, a second member loosely mounted on the valve stem, means for oscillating said second member during the operations of the valves, means for holding said members in operative relation to one another, and coacting means arranged on the adjacent end faces of the affixed and loosely mounted members for affecting a frictional binding action between said members and the valve when the second member is oscillated in one direction and permitting a subsequent release of the parts when the second member is oscillated in the opposite direction.
16. In a rotating device for a reciprocating valve comprising a member affixed to the valve stem, a second member loosely mounted on the valve stem and in axial alignment with the affixed member, means for oscillating said second member during the operations of the valve, and means at the respective end portions of the affixed

and loosely mounted members for effecting a frictional clutch engagement between the members and the valve when the second member is oscillated in one direction.

17. In a rotating device for a reciprocating valve comprising a member affixed to the valve stem, a second member loosely mounted on the valve stem, means for oscillating said second member during the operations of the valve, a casing affixed to the first member and overlying the end of the second member, thereby holding said members in operative relation to each other, cooperating means arranged on the adjacent end portions of the affixed and loosely mounted members to effect a binding action between the parts and the valve when the valve is moved in one direction and to permit a release thereof when moved in the opposite direction.

18. In a rotating device for a reciprocating valve comprising a member affixed to the valve stem, a second member loosely mounted on the valve stem, means for oscillating said second member during the operations of the valve, and axially aligned cooperating cammed surfaces between said members to effect a frictional engagement between the members and the valve when the valve is moved in one direction and a subsequent release thereof when the valve is moved in the opposite direction.

19. In a rotating device for a reciprocating valve comprising a member affixed to the valve stem, a second member loosely mounted on the valve stem, means for oscillating said second member during the operations of the valve, and coactive surfaces arranged on the affixed and loosely mounted members for effecting a frictional engagement between said members and the valve when the valve is moved in one direction and a subsequent release thereof when moved in the opposite direction.

20. A reciprocating device for a reciprocating valve comprising a member affixed to the valve stem, a second member loosely mounted on the valve stem and in axial alignment with the affixed member, means for oscillating said second member during the operations of the valve, and cooperating surfaces on the adjacent faces of the affixed and loosely mounted members for effecting a frictional engagement between the members and the valve when the valve is moved in one direction and a subsequent release thereof when the valve is moved in the opposite direction.

In testimony whereof I hereunto affix my signature.

WILMER G. BUCK.
